UNITED STATES PATENT OFFICE.

CHARLES BUDAI, OF CHICAGO, ILLINOIS.

SPONGE-RETAINING AND WATER-SUPPLYING DEVICE.

1,114,678.

Specification of Letters Patent.

Patented Oct. 20, 1914.

Application filed December 6, 1913. Serial No. 805,162.

To all whom it may concern:

Be it known that I, CHARLES BUDAI, a subject of the King of Hungary, residing at Chicago, in the county of Cook and State 5 of Illinois, have invented certain new and useful Improvements in Sponge-Retaining and Water-Supplying Devices to be Applied to the Heads of Horses, of which the following is a specification.

10 The present invention relates to new and useful improvements in means for securing and applying water to the sponge when applied to the head of a horse.

15 In summer months, when horses become over-heated by the hot rays of the sun, it has been the usual practice to apply a cold wet sponge to the head of the horse, and it is an object of the present invention, to provide means for retaining the sponge upon 20 the head of the horse, and also for supplying the sponge continually with the water.

25 A further object of the present invention is to provide a device of the aforesaid character, comprising a comparatively few parts, which may readily be assembled and applied to the head of the horse, and which will be comparatively inexpensive in the cost of manufacture, thereby, rendering the same commercially desirable.

30 With the above and other objects in view, the invention consists of the novel features of construction, combination, and arrangement of parts, as will be hereinafter fully described and particularly pointed out in 35 the appended claims.

In the drawings, Figure 1 is a side view 40 illustrating one embodiment of the present invention. Fig. 2 is a sectional elevation of the same, and Fig. 3 is a transverse section on the line $\alpha-\alpha$ of Fig. 2.

Referring to the drawings, wherein like 45 and corresponding parts are designated by similar reference characters, throughout the several views used, the numeral 1 indicates a sponge, adapted to be placed upon the head of a horse, which is indicated as at 2.

The sponge 1 is adapted to be placed within an opening 3, formed within the lower section 4, or the retaining device, which is 50 made preferably of flexible material, such as leather or the like. The section 4 of the device has extending laterally therefrom straps 5, which are adapted to be secured to the bridle carried by the horse's head. 55 The rearwardly extending lap 6, is carried by the section 4, and rests upon the neck of

the horse, and openings 7 are formed in the portion 6, through which extend the ears of the horse, when the device is applied to the horse's head.

60 Adapted to rest on the sponge 1, is a liquid containing receptacle 8, which is made of any preferred or well-known construction, or of the configuration as shown. This receptacle is covered by a flexible material 9, such as leather or the like. The section 4 has eyelets 10, which are adapted to be placed over the projections 11, carried by the lower end of the receptacle 8, whereby the receptacle will be held in its correct 65 position.

To give the device a neat appearance when applied to the head of the horse a hood or canopy 12 is placed over the device, having an opening formed therein for the 70 reception of the neck of the receptacle 8. This hood or upper section 12, has formed therewith eyelets 13, adapted to be placed over the buttons 14, carried by the neck of the receptacle, thereby providing means for 75 holding the cover in place. 19 is a screw cap or cover for the receptacle 8.

To supply the sponge 1 continually with water I have provided within the receptacle 8, a tube 15, having a plurality of openings 80 16, formed therein, for permitting the water to flow from the receptacle, into the tube. Leading from the tube 15, are outlet openings 17, which extend through the base of the receptacle and the cover encircling the 85 same, whereby the water may be fed to the sponge. When it is desired to fill the receptacle 8, the screw-cap 19 is removed and a sufficient quantity of water is poured in and the cap put on. This will last for a 90 considerable time without replenishing. An air-tube indicated by the numeral 18, may lead to the receptacle, to cause the water to properly flow through the space when the receptacle is closed, and 20 is a valve for 95 regulating or shutting off the air supply.

I claim;

1. A protector adapted for attachment to a horse's head, comprising a water receptacle, a sponge holder arranged below said 100 receptacle and having a bottom opening through which a sponge is arranged to protrude to rest upon the horse's head, and means within said receptacle for feeding water to the sponge consisting of a 105 perforated tube provided with outlets projecting into the sponge receptacle.

2. A protector for animals comprising a water receptacle having an air inlet and a normally-closed filling neck, a perforated tube within said receptacle having discharge outlets, a sponge holder arranged below said receptacle and having a bottom opening through which a sponge is arranged to protrude to rest on the animal's head, a canopy provided with an opening to receive the neck of the water receptacle, and means for securing the canopy to said neck.

3. The combination with a water receptacle provided with an upwardly extending central filling neck and a screw cap closure for said neck, of a sponge-holder depending below said receptacle and provided with a

sponge and having a bottom opening through which the sponge is arranged to protrude, means within the receptacle for supplying water to the sponge-holder, a canopy having an opening to receive said neck, and means for securing said canopy upon the neck.

In testimony whereof I have hereunto set my hand this 5th day of November, A. D. 1913.

CHARLES X. BUDAI.
mark.

In presence of—
JOHN BELL,
JOSEPHINE VERING.
